UNITED STATES PATENT OFFICE

YERMIE G. STERN, OF NEW YORK, N. Y.

DESIGN FOR A DRESS

Application filed October 20, 1931. Serial No. 41,464. Term of patent 3½ years.

To all whom it may concern:

Be it known that I, YERMIE G. STERN, a citizen of the United States, residing at New York city, in the county of New York and State of New York, have invented a new, original, and ornamental Design for a Dress, of which the following is a specification, reference being had to the accompanying drawing, forming part thereof.

In the drawing:

The figure is a perspective view of a dress

showing my new design. The back of the dress is of the same general appearance as the front with the exception that the figured design of the goods appears in the center of the back of the bodice in a contra-distinction to the design of the front of the bodice as shown.

I claim:

The ornamental design for a dress as shown and described.

YERMIE G. STERN.
